UNITED STATES PATENT OFFICE.

GEORGE CADE, OF MEMPHIS, TENNESSEE, ASSIGNOR OF ONE-HALF TO JOHN W. MAUMEE, OF SAME PLACE.

DEVICE FOR HANDLING SHELF GOODS, &c.

SPECIFICATION forming part of Letters Patent No. 395,949, dated January 8, 1889.

Application filed July 10, 1888. Serial No. 279,564. (No model.)

To all whom it may concern:

Be it known that I, GEORGE CADE, a citizen of the United States, and a resident of Memphis, in the county of Shelby and State of Tennessee, have invented certain new and useful Improvements in Devices for Handling Shelf Goods, &c.; and I do hereby declare that the following is a full, clear, and exact description of the invention, which will enable others skilled in the art to which it appertains to make and use the same, reference being had to the accompanying drawings, which form a part of this specification, and in which—

15 Figure 1 is a perspective view of my device or apparatus when not in use. Fig. 2 is a similar view of the apparatus as when in use; and Figs. 3 and 4 are perspective detail views of the head or upper part of the device.

20 Like letters of reference indicate corresponding parts in all the figures.

My invention has relation to devices for handling goods which are disposed upon shelves out of reach except by means of a ladder, or which are suspended from hooks to the under side of the ceiling of a store or warehouse; and it consists in the construction and combination of parts of the apparatus which will be hereinafter more fully described, 25 whereby a person may handle these goods—that is, take them down and again replace them—in a simple and expeditious manner without the use of a ladder, thereby saving time, labor, and annoyance in showing goods 30 to purchasers and others.

Reference being had to the accompanying drawings, the letter A designates a pole of any suitable length and material, the upper end of which is beveled and provided, by preference, with a disk or plate, B, of rubber, leather, or other suitable material. To the back part of the pole, opposite to its beveled side or face, is attached a hook, C, which may be made of wire of the form shown in the drawings, or any other form of hook may be employed, if preferred. To opposite sides of the upper part of the pole, and at right angles to the rearwardly-projecting hook, is fastened a pair of arms, D D, the outwardly-projecting 45 ends of which form eyes E E for the insertion

of the wire loop F. This loop is preferably made of tempered steel wire of suitable thickness, or flat steel spring; and the inner ends of the loop, after passing through the guide-eyes E E and guide or keeper O on the back 50 part of the pole, are fastened to the upper ends of a pair of arms, G, which, in conjunction with the lower arms, H H, constitute a toggle-joint or toggle-lever, the upper pair of arms, G G, crossing each other and having 55 their fulcrum upon a pin or bolt, I, inserted into the pole. The lower ends of the lower-most arms H H are connected and fastened upon a hook, J, at the upper end of the sliding rod K, which slides through staples or 60 keepers L, inserted into the back part of the pole. Rod K is provided at its lower end with a loop, M, encircling the pole, and having a projection, N, on one side, which forms a convenient handle for operating the rod. 65 This device or apparatus is used as follows: If it is desired to remove an article standing upon a shelf or suspended from a hook—as, for example, a boot—the loop F at the upper end of the pole is drawn over the article—as, 70 in the present illustration, the boot-leg—and by then pushing the sliding rod K in an upward direction the loop will be contracted, so as to grasp or bind upon the article inserted through it, as represented in dotted lines in 75 Fig. 2 of the drawings, when the article in question may readily be lifted off of the hook or shelf, as the case may be, and taken down for the inspection of the customer. By relaxing the loop, which is done simply by releasing the hand from the sliding rod, the spring in the loop will bring itself back to its normal position and the article is readily and instantly released. When, after examination, 80 it is again desired to replace it, this is done by again fastening it in the loop, as aforesaid, and then lifting it up to its proper place upon the shelf or under the ceiling, after which the loop is relaxed by pulling rod K down, and the apparatus is detached from the article and 85 placed in one corner, out of the way and ready for use.

The advantages of this apparatus are so obvious as to require no lengthy explanation. It can be manufactured at a small cost, is 90

always ready for use, and will handle the articles without the slightest injury to the same. If desired, in handling fine goods the flexible loop F may be covered with cloth, rubber, or other suitable material, to prevent abrasion of the articles grasped by it. The upper beveled part of the pole being covered with a disk of leather or rubber prevents chafing of the article during the process of applying or again removing the device, and the hook C at the upper end of the pole will be found convenient for use sometimes when there is no necessity of employing the loop.

Having thus described my invention, I claim and desire to secure by Letters Patent of the United States—

1. The combination of the pole, the sliding rod, the toggle joint or lever, the flexible loop, and the arms for guiding and supporting the

latter, substantially as and for the purpose shown and set forth.

2. A compound implement comprising the pole beveled at its upper end, the arms attached to opposite sides of the same and provided with eyes at their outer ends, the flexible loop inserted through said eyes, the toggle joint or lever, the sliding rod for operating the latter, and the fixed hook, all constructed and combined to operate substantially as and for the purpose shown and set forth.

In testimony that I claim the foregoing as my own I have hereunto affixed my signature in presence of two witnesses.

GEORGE CADE.

Witnesses:

L. D. ADAMS,
P. M. GOODMAN.
